4 Claims. (Cl. 19—135)

This invention of improvements in or relating to weighting mechanism for the drawing rollers of combing machines and other machines for the treatment of textile fibers refers more particularly to mechanism for quickly relieving, and re-applying, weight to the covered top rollers of the drawing-head of a machine of the kind referred to.

It is well known in connection with the weighting of drawing rollers, especially where the top rollers are leather covered, that it is desirable, when the machine is stopped for any considerable length of time, that the top rollers should be relieved of the influence of the weights to avoid the formation of "flats" on the covering of said top rollers.

Various means for accomplishing this purpose have been proposed, some operated by rotation of a screw by means of handwheel and others by movement of a lever, usually through a relatively large angle, thus occupying an appreciable amount of the time of an operative. If the operative be careless, or, as often as not, is in a hurry to get this part of the work over, the unweighting is sometimes not properly performed, with consequent risk of damage to the top rollers.

A further disadvantage experienced with some known weight-relieving mechanisms is that when the weighting hooks are removed from the arbors of a top roller in order that said top roller may be lifted out for cleaning or changing, there is a tendency for the weight wires to fall out of position and sometimes to be not readily accessible for replacement.

This invention contemplates the provision of mechanism which permits the weight to be lifted from the top rollers of a drawing-head sufficiently to prevent the formation of flats on the top rollers, and reapplication of said weight, with a minimum of effort on the part of the operative, which also permits the top rollers to be quickly relieved of their weight by a further slight effort on the part of the operative so that said rollers can be lifted out for cleaning or changing, and further, which prevents the rollers from being unweighted whilst the machine is running and alternatively prevents the machine from being set in motion if the rollers are unweighted. A still further feature is that the weighting hooks from which the weights are suspended are so arranged that when lifted from the rollers they are retained in a conveniently accessible position in the machine, whereby to facilitate the reweighting of the top rollers.

Mechanism according to the invention, and particularly as applied to the draw-head of a combing machine for combing textile fibers, incorporating a group of top and bottom rollers, 5 includes a set of independent weights threaded on to weighting hooks for suspension from the top rollers of said draw-head, a bridge piece penetrating said weights in a direction at right-angles to the axes of said top rollers, said bridge piece being carried between bearing brackets secured to the frame of the machine, with freedom for limited up and down movement between said brackets, a shaft journalled in said brackets in parallelism with said bridge piece, a cam fast on said shaft, at least one lobe of said cam being higher than the other or others, a handle on said shaft whereby said shaft may be turned about its axis, within limits, a finger or bolt pivotally mounted on the boss of one of said 10 bearing brackets, whereby, when the machine is running, turning of the handle to relieve the weighting of the top rollers is prevented by the obstruction of said bolt by the setting-on rod of the machine, but, when the machine is stopped, turning of said handle to relieve the weighting of the top rollers is permitted, as the projecting bolt is then free to slide in a groove in said setting-on rod which is brought into the path of movement of said bolt when the said rod is operated to stop the machine, the engagement of said bolt with said rod preventing endwise movement of said rod to start the machine.

An embodiment of the invention will now be described with the aid of the accompanying drawings in which Fig. 1 is a fragmentary side elevation of a draw-head of a combing machine with weight-relieving mechanism according to the invention applied thereto; Fig. 2 is a fragmentary side view of weight-relieving mechanism shown in Fig. 1; Fig. 3 is a plan view of a detail part, later to be referred to; the parts in the foregoing figures being assumed to be in the position occupied when the combing machine is running; Figs. 4 and 5 are similar views to Figs. 2 and 3, but in this case the combing machine is assumed to be stopped and the weight-relieving mechanism moved to a "first lift" position to relieve the top-rollers of the weight while also preventing the machine from being restarted; the top rollers, however, being incapable of removal from the roller stands; Figs. 6 and 7 are similar views to Figs. 4 and 5, but with the weight-relieving mechanism moved to a "second lift" position to free the top rollers and permit of their removal from the roller stands while still

preventing the machine from being set in motion.

The same reference characters indicate corresponding parts in the several figures of the drawings which show only so much of a combing machine as is necessary for a clear understanding of the invention.

Referring to Fig. 1, which shows in side elevation a draw-box head of a combing machine, 10 indicates the frame of the machine, 11 the roller stands, and 12, 13 the top and bottom drawing rollers. There is provided below the draw-head a short shaft 14, hereinafter referred to as a cam-shaft, journaled in bearings in a pair of spaced brackets 15, 16 carried by the frame 10.

Fixed on the cam-shaft 14 is a cam 17 of an axial dimension slightly less than the distance between the adjacent faces of the bearing brackets 15, 16. The cam 17 is formed with three lobes 18, 19, 20, providing cam rises extending longitudinally of said cam, the central lobe 19 projecting further from the axis of the cam shaft 14 than the outer lobes 18, 20, see Figs. 2, 4 and 6. Although only the central lobe 19 and the outer lobe 18 are used in the arrangement shown in the drawings, the second outer lobe 20 is provided to obviate the need for right and left-handed cams. Mounted for vertical sliding movement within the bearing brackets 15, 16 and in close proximity to the cam 17 is a bridge-piece 21 the under side of which is formed with a cam surface 21a while the top side presents a plane surface 21b which in one condition of use affords bearing for a set of weights 22 each having an orifice 22a enabling said weights to be threaded over the bridge-piece 21, the cam shaft 14 and the cam 17, and located between the bearing brackets 15, 16. When the machine is working, the bridge-piece 21 rests by its ends 21c, 21d on the bosses 15a, 16a of the respective bearing brackets 15, 16, see Figs. 1 and 2, the upper part of each of said bosses being formed with a flat to receive the bridge-piece 21.

There is a weight 22 for each top roller 12 to be weighted, and each weight 22 is suspended by a pair of hooks 23 from the arbors of the respective top roller 12 in known manner. Each weight 22 is narrow in relation to its depth, and in each narrow side adjacent to the top of the weight there is formed an open-ended groove or recess 22b whereby in effect lugs 22c are provided on opposite sides of the weight 22. The lower ends of the weighting hooks 23 penetrate holes in the lugs 22c and are screw-threaded and provided with washers 24 and nuts 25 to secure the weights on the hooks. When the hooks 23 are lifted from the arbors of the top rollers 12, the lower ends of said hooks, where they project through the lugs 22c, come into contact with shoulders 22d formed by the floors of the respective recesses 22b, whereby undesirable movement of the hooks 23 is restrained and the hooks 23 are held in accessible position, thus facilitating the replacement of the hooks 23 in the re-weighting of the top rollers 12.

The cam-shaft 14 projects at one end through the boss 15a of the bracket 15 and is there fitted with a stop 26a adapted to abut against a stop 15b on the boss 15a of the bracket 15 to limit the forward movement of the handle 26. Similar stops 26b, 15c respectively, are also provided for use for the same purpose with a machine of opposite hand.

Pivotedly connected to a lug 15d projecting from the boss 15a of the bracket 15 is a finger

or bolt 27 extending in an upwardly inclined direction with its free end penetrating a hole in a guide bracket 28 secured to the outer face of the bearing bracket 15. The guide bracket 28 5 also affords a bearing for the usual setting-on rod 29 of the machine which has on its underside a notch 29a wide enough to allow entry of the bolt 27 therein.

In one position of use the notch 29a is in the path of movement of the bolt 27, while in another position of use the setting-on rod 29 interferes with the movement of the bolt 27.

The operation of the apparatus is as follows:

Assuming that the weighting is correctly applied to the top rollers 12, i. e., the weights 22 are suspended from the arbors of the top rollers 12 by means of the weighting hooks 23 and are clear of the bridge 21, and the machine is working, the position of the handle 26 on the cam-shaft 14 will be vertically downwards i. e., at six o'clock, and the setting-on rod 29 will be in a position which prevents the bolt 27 from sliding through the guide bracket 28, see Figs. 2 and 3, and, consequently, the handle 26 is held against movement to relieve the weighing on the rollers. When the machine is stopped, the setting-on rod 30 is in a position where the notch 29a in the underside of the setting-on rod 29 is in register with the hole in the guide bracket 28 through which the bolt 27 slides, and consequently there is free passage for the bolt 27 through the bracket 28, see Figs. 4 and 5.

If it is desired to release the weight from the top rollers 12 to obviate the formation of "flats" 35 on the top rollers during a prolonged stoppage of the machine, then the handle 26 is moved approximately to seven o'clock position whereby the cam shaft 14 is given a partial rotation, whereupon one of the outer lobes, e. g., the lobe 18, is caused to bear against and move the bridge-piece 21 vertically upwards to lift simultaneously all the weights 22 just sufficiently to relieve the weighting on the top rollers 12, see Fig. 5. This movement of the handle 26 is so slight that it entails very little effort on the part of the operative to relieve the weighting instantly.

This movement of the handle 26 causes the bolt 27 to be slid through the guide bracket 28 into engagement with the notch 29a in the setting-on rod 29, see Figs. 4 and 5, thereby preventing endwise movement of the rod 29 and consequently rendering it impossible for the machine to be restarted while the top rollers 12 are unweighted.

If, however, it is desired to remove one or more 55 of the top rollers 12 for clearing or for change of the rollers, the handle 26 is moved to a position approximating to nine o'clock, thus turning the cam-shaft 14 and causing the central lobe 19 of the cam 17 to press against and lift the bridge piece 21, and the weights 22, now sustained by said bridge piece 21, to a greater extent, see Fig. 6, so that the weighting hooks 23 may be lifted clear of the arbors of the top rollers 12 to permit said rollers to be easily removed. Undesirable 60 downward movement of the weighting hooks 23 is restricted by the bottom ends of the hooks 23 abutting against the shoulders 22d formed by the floors of the recesses 22b in the weights 22, whereby the weighting hooks are retained in conveniently accessible position. The bolt 27 projects further through the guide bracket 28, but still engages the notch 29a in the setting-on rod 29, see Fig. 7, to prevent endwise movement of the rod 29. The movement of the handle 26 is restricted in this direction by the stop 26a on the 65 70 75

handle 26 abutting against the stop 15b on the adjacent bearing bracket 15, see Fig. 6.

When the weighting is to be applied to the top rollers 12, the weighting hooks 23 are replaced in position over the arbors of the top rollers 12 and the handle 26 is returned to initial position, whereupon the turning of the cam-shaft 14 and cam 17 permits the bridge piece 21 to fall by gravity until the weights 22 are again free of the bridge piece 21 and suspended on the weighting hooks 23 from the top rollers 12. On the completion of this movement the bolt 27 is withdrawn from engagement with the notch 29a in the setting-on rod 29 which is thus made free to be moved to start the machine.

Movement of the handle 26 to relieve the weighting while the machine is in motion is prevented, as the setting-on rod 29 is in the path of movement of the bolt 27, thus rendering it impossible to move the handle 26, see Figs. 2 and 3.

It will be seen from the foregoing description that the operation of relieving the weighting of the top rollers of a draw-box can be effected quickly with a minimum of effort on the part of an operative, and as easily re-applied, and that, when the weighting is "off" the rollers, the machine cannot be restarted until the weighting has been restored.

Further, the top rollers cannot be unweighted while the machine is running.

What is claimed is:

1. In a draw-head for combing machines and other machines for the treatment of textile fibres, incorporating a group of top and bottom rollers, weighting mechanism for said rollers, including fixed bearing brackets, a set of individual weights, one for each top roller, weighting hooks for suspension of said weights from the top rollers, a bridge-piece penetrating said weights in a direction at right angles to the axes of said top rollers, said bridge-piece being carried, with freedom for

limited up-and-down movement, between said brackets, a cam shaft journalled in said brackets in parallelism with said bridge-piece, a lobed cam fast on said shaft, at least one lobe of said cam being higher than any other lobe, said lobes being operative to lift said bridge-piece, a guide on one of said brackets, a setting-on rod for the machine, said setting-on rod being formed with a groove, a handle on said shaft movable within limits, a bolt pivotally mounted on said handle and projecting through said guide, said bolt being obstructed by the setting-on rod when the machine is running, whereby to prevent turning of said handle to turn said cam and relieve the weighting on the top rollers and, when the machine is stopped, being free to be slid into engagement with said groove, whereby to prevent endwise movement of said setting-on rod to start the machine.

20 2. Weighting mechanism for the drawing rollers of combing machines and other machines for the treatment of textile fibers as claimed in claim 1 in which the cam lobes are so devised that a slight initial turning movement of the handle suffices to release the weighting of the top rollers, and continued turning movement of said handle effects complete release of the top rollers.

3. Weighting mechanism as claimed in claim 1 in which the cam is reversible and formed with three lobes providing cam rises extending longitudinally of said cam, the central lobe projecting further from the axis of the cam-shaft than the outer lobes.

35 4. Weighting mechanism as claimed in claim 1, in which each weight is narrow in relation to its depth and is formed in each narrow side adjacent to the top of the weight with an open-ended recess whereby to provide lugs on each side of the weight adapted for penetration by the lower ends of the weighting hooks.

DONALD PIERREPONT.
